CLAIM

I claim, the ornamental design for a digital television receiver displaying design on screen, as shown and described.

DESCRIPTION

FIG. 1 is a top and front perspective view of a digital television receiver displaying design on screen, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of the digital television receiver is included for the purpose of illustrating a portion of the article and forms no part of the claimed design.
